United States Patent Office.

ANDREW MURDOCK, OF BROOKLYN, E. D., NEW YORK.

Letters Patent No. 106,191, dated August 9, 1870.

BASE-BURNING FIRE-PLACE HEATER.

The Schedule referred to in these Letters Patent and making part of the same

To all whom it may concern:

Be it known that I, ANDREW MURDOCK, of Brooklyn, E. D., in the county of Kings and State of New York, have invented an Improvement in Fire-place Heaters; and the following is hereby declared to be a correct description thereof.

Fire-place heaters have been made with a descending draught that conveys away the products of combustion into the base of the stove, previous to escaping into the chimney. In this class of heaters the descending draught has been at the back or sides of the fire-pot, and generally by a pipe outside the casing, forming the combustion-chamber.

My invention is made for equalizing the heat, and preventing any portion of the stove or heater becoming too highly heated, and also for insuring the necessary temperature in the front portion of the stove, for heating the basement or room in which the fire-place heater is located.

I make use of a double casing in the front part of the stove, below the top of the fire-pot, said casing forming a descending flue that opens at top into the combustion-chamber, and at the bottom into flues at the base of the heater. By this construction the products of combustion are directed toward the front of the heater, thereby lessening the intensity of the heat at the confined rear portion of the combustion-chamber, and then the products of combustion pass up the flue or flues at the rear, and the heated atmosphere also ascends to the rooms above through air-pipes, as now usual.

In the drawing—

Figure 1 is a vertical section at the line $z z$ of fig. 2; which

Figure 2 is a sectional plan at the line $y y$ of fig. 1; and

Figure 3 is a vertical section at the line $z z$.

The base of the stove is made of the bottom plate a , above which are plates forming side-flues, $b b$, and a back flue, c , on three sides of the ash-pit or box d .

The plate e , over the flues $b c$, forms the base for

the fire-pot g and casing f , and over the casing f is a top plate, h , with an opening, i , for fuel to be introduced into the magazine or hopper k .

The fire-pot g and casing f coincide at the back part of the heater, but the casing is shaped as in fig. 2, so that there will be a segmental annular space, l , between the fire-pot and casing, and this is covered at the top by a similarly-shaped plate, n . At the level, or nearly so, of the top of the fire-pot, and in this plate n , are openings toward the front part. I prefer to have a number of holes, as seen in fig. 2.

This space l forms a descending flue, that opens into the flues $b b$, by means of holes $o o$, through the plate e .

It will now be understood that the fire burns at the base of the magazine k , and the products of combustion ascend into the chamber u , between the magazine k and casing f , and descend, through the flue l , to the flues $b b$ and c , and thence pass to the chimney-flue v .

A damper, at s , allows, when open, a direct draught to the flue v in kindling the fire, and a damper, t , at the base of the flue v , admits air from the ash-box or pit to lessen the strength of the draught when the fire is burning too strongly.

A slide or cover at r facilitates the cleaning of the back flue from earthy accumulations.

I claim as my invention—

1. The descending flue l , between the fire-pot g and front portion of the casing f , opening at the top into the combustion-chamber u , and at the bottom into the side flues $b b$ of the fire-place heater, substantially as set forth.

2. The damper s , below the ascending flue v , in combination with the flues c , $b b$, and l , as and for the purposes set forth.

Dated July 9, 1870.

ANDREW MURDOCK.
